UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

ROCK DRILL

Application filed February 2, 1929. Serial No. 337,061.

My invention relates to rock drills and particularly to devices for cleansing the hole during drilling.

An object of my invention is to provide an improved rock drill having improved means for effecting a hole blowing operation. Another object of my invention is to provide an improved hole blowing device which shall be of very simple and rugged construction. A further object of the invention is to provide an improved hole blowing device capable of being easily and quickly controlled by the operator. A more specific object of the invention is to provide an improved hole blowing device of the type adapted to close a free exhaust port in the cylinder and simultaneously effect continuous supply of motive fluid to the front end of the cylinder. Other objects and advantages of the invention will appear during the course of the following specification and claims.

In the accompanying drawing I have shown for purposes of illustration one embodiment which my invention may assume in practice.

In this drawing,—

Fig. 1 shows a longitudinal section through a rock drill with the ends broken away, parts being shown in elevation.

Fig. 2 is a fragmentary sectional view on line 2—2 of Fig. 1 through my improved hole cleansing means.

Fig. 3 is a similar transverse section on line 3—3 of Fig. 1.

Fig. 4 is a detail perspective view of the slide valve of my improved hole cleansing means.

Fig. 5 is a developed sectional view showing passages controlled by the slide valve.

Referring to the particular embodiment of my invention as herein shown, the drill with which I have shown my improvement associated comprises a cylinder 5 having a piston 6 reciprocable therein, which piston has an integral forwardly extending striking bar 7 adapted to hammer on the shank 8 of a rock drill steel. This drill steel has a longitudinal passage 9 extending to its cutting end and this passage may be supplied with compressed air, a cleansing liquid, or a mixture of both,

for the purposes of cleansing the cuttings and removing them from the hole. In this embodiment there is illustrated a central water tube 10 having its forward end received loosely in bore 9 of the drill steel, as is common in the art. During normal operation, when the piston is in the rearward part of its travel, some pressure fluid passes down through the grooves 11 on the striking bar 7 into the chamber surrounding the shank of the drill steel and thus passes into the bore 9 where it mixes with the water flowing through tube 10, if such tube be provided, and assists in cleansing the hole. This is accomplished by reason of the fact that the grooves 11 withdraw into the cylinder from the buffer ring 12 which is interposed between the cylinder and the chuck housing or front cylinder head member 13. In drilling deep holes and particularly in certain kinds of formation, this supply of pressure fluid is not sufficient to cleanse the cuttings from the hole and my invention pertains to an improved device for intermittently stopping the operation of the hammer piston and introducing a much larger quantity of pressure fluid to the bore 9 for blowing the cuttings from the hole.

Any suitable fluid distribution means for effecting admission and exhaust of motive fluid may be employed and in the machine shown such fluid distribution means includes a fluid actuated reciprocable valve 14 in axial alignment with the cylinder. Motive fluid is supplied to the machine through an inlet passage 15 and passes to the rear end of the cylinder through the inlet groove 16 and around the end of the valve when the valve is in the position shown in Fig. 1. The valve has a large diameter portion 17 which is received in an enlarged bore 17' of the valve chest, a reduced portion 18 providing a constant pressure area 19, and a still further reduced end portion 20. An outside annular groove 22 is formed in the valve for purposes which will presently appear. The rearward area on the large diameter portion 17 communicates with the cylinder by means of a throw passage 21 shown in dotted lines. A passage 23 connects an annular groove 24 in the valve chest with the front end of the cyl-

inder. The fluid distribution means also includes a free cylinder exhaust port 25 controlled by the piston. Passage 23 serves to admit pressure fluid from the valve chest to the forward end of the cylinder when the valve is thrown to its forward position.

In operation, pressure fluid passes through the inlet 15 to the rear end of the cylinder when the valve is in the position shown and 10 drives the piston forwardly to strike a blow on the drill steel. The valve is held in this position by live pressure acting on the forwardly facing areas of the valve. During the forward stroke the throw passage 21 is 15 uncovered, admitting live pressure fluid to the rear surface on the large diameter portion 17 to throw the valve forwardly. This area is of sufficient extent to overcome the pressure acting on the forwardly facing areas of 20 the valve which are exposed to pressure in the rear end of the cylinder. The piston uncovers the cylinder exhaust port 25 and the rear end of the cylinder is exhausted. When the valve is thrown, its front end cuts off admission to the rear of the cylinder and admission takes place to the front end of the cylinder from inlet groove 16 around annular groove 22 on the valve, groove 24 in the valve chest and passage 23. The piston is then 25 driven rearwardly and after cylinder exhaust port 25 is covered, compression takes place in the rear end of the cylinder and this compression pressure acts on the forwardly facing surfaces of the valve to throw the same rearwardly to the position shown, and the same cycle of events is repeated over and over. It will be understood that the rear surface of the enlarged portion 17 of the valve will have been relieved of pressure since passage 30 35 21 has been in communication with the exhaust and the only substantial pressure which needs to be overcome in throwing the valve rearwardly is the constant pressure acting on shoulder 19. When the piston is in the rear 40 end of its stroke, the grooves 11 will serve to establish communication between the front end of the cylinder and the chamber surrounding the shank 8 of the drill steel.

My improved hole blowing device will next 50 be described. An integral boss 26 projects laterally from the cylinder adjacent the cylinder exhaust port and in this boss are formed a pair of longitudinal guiding grooves 27 which are connected in front of the cylinder 55 exhaust port by a curved groove of the same depth. In these guiding grooves 27 there is mounted a flat slide valve 28 having guides 29 at opposite sides which are received in the guiding grooves 27. This valve has a small 60 handle 30 attached thereto which projects laterally in such position as to be easily grasped by the operator. The valve and handle are provided with a small bore 31 which receives a plunger 32 which is pressed by a spring 33 65 so that its curved end 34 moves into a slight

conical recess 35 whereby the valve is normally retained in inoperative position. A passage 36 extends longitudinally through the cylinder wall and communicates directly with the free cylinder exhaust port at one end and with the enlarged bore 17' of the valve chest at its other end in about the same transverse plane as the throwing passage 21. When it is desired to effect a hole blowing operation, the operator moves the handle 30, 70 whereupon the slide valve covers the exhaust port 25 and prevents exhaust of motive fluid from the front end of the cylinder. A pressure will be very quickly built up at this point which is simultaneously transmitted through the passage 36 to the large throwing surface on portion 17 of the valve whereby the valve is held continuously in its forward position. Motive fluid then passes continuously through 75 passage 23 to the front end of the cylinder and, since it is not permitted to escape through port 25, a large quantity will pass through grooves 11 in the striking bar and build up a substantial pressure in the chamber surrounding the shank of the drill steel. 80 This supplies fluid at live pressure to the bore in the drill steel, which is very effective in blowing the cuttings from the drilled hole. The slide valve 28 is maintained in its closed 85 position by the pressure of the fluid in the cylinder. As soon as the hole is cleaned, the operator again opens the exhaust controlling valve and normal operation of the machine is automatically resumed.

As a result of my invention it will be apparent that an improved device of very simple and rugged construction has been provided for effecting a hole blowing operation, and that at the same time means are provided under the control of a slide valve for causing 100 the distribution valve to be held in such position as to supply motive fluid to the front end of the cylinder continuously. The slide valve of my invention has very decided advantages over an oscillating valve from the 105 standpoint of ease of operation and simplicity of construction.

While I have in this application specifically described one embodiment which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a rock drill, the combination of a cylinder having ports and passages for the admission and exhaust of motive fluid, a piston reciprocable therein, said cylinder having intermediate its length and controlled by the piston an exhaust port, a slide valve arranged alongside the cylinder and adapted in one position to close the exhaust port, said slide 115 120 125 130

valve being maintained in its closed position by the pressure of the fluid in the cylinder, and a drill bit having a longitudinal passage for the motive fluid from the end of the cylinder to its cutting end.

5. 2. In a rock drill, the combination of a cylinder, a piston reciprocable therein, fluid distribution means therefor including an exhaust port in the cylinder wall intermediate its length and governed by the piston, a drill steel having a longitudinal passage for motive fluid, means for establishing communication between said passage and the front end of the cylinder when the piston is in the 10 rear end of the cylinder, said cylinder exhaust port being normally open when said piston is in the rear end of the cylinder, and a slide valve arranged exteriorly and longitudinally of the cylinder adapted to be moved 15 into position to close said exhaust port for effecting a hole blowing operation, said slide valve being maintained in its closed position by the pressure of the fluid in the cylinder.

3. In a rock drill, the combination of a 20 cylinder, a piston reciprocable in said cylinder, fluid distribution means for controlling admission and exhaust of motive fluid including an exhaust port in said cylinder intermediate its length and governed by the piston and a distributing valve adapted in one position to effect admission of motive fluid to the front end of the cylinder, a drill steel arranged to be percussively actuated by said piston and having a longitudinal passage for 25 motive fluid to its cutting end, means for establishing communication between said passage and the front end of said cylinder when the piston is in the rear end of the cylinder, and means for simultaneously closing 30 said exhaust port and effecting supply of pressure fluid to an area on said valve to hold the latter in position to admit motive fluid continuously to the front end of the cylinder to effect a hole blowing operation.

45. 4. In a rock drill, the combination set forth in claim 3 wherein said last mentioned means comprises a valve for closing said exhaust port and a passage, the pressure in which is controlled by said valve, for admitting pressure fluid to said area on the distribution valve.

5. In a rock drill, the combination set forth in claim 3 wherein said last mentioned means comprises a valve arranged exteriorly of the 55 cylinder for closing said exhaust port and a passage leading from said exhaust port to said area on the distribution valve and arranged to be supplied with pressure fluid from the front end of the cylinder when the 60 exhaust port is closed.

6. In a rock drill, the combination set forth in claim 3 wherein said last mentioned means comprises a slide valve arranged exteriorly of the cylinder and adapted to close said 65 exhaust port, and a passage leading from said

exhaust port through the cylinder wall to said area on the distribution valve.

7. In a rock drill, the combination of a cylinder, a piston reciprocable therein, fluid distribution means for effecting admission and exhaust of motive fluid, a drill steel arranged to be percussively actuated by said piston having a longitudinal passage for pressure fluid to its cutting end, means for placing said passage in communication with the cylinder when the piston is in the rearward portion of its stroke, said cylinder having intermediate its length and governed by the piston an exhaust port, and means for closing said exhaust port to effect a hole blowing operation comprising a valve arranged exteriorly of and slideable longitudinally of the cylinder to effect closing of said exhaust port at will, said slide valve being maintained in its closed position by the pressure of the fluid in the cylinder.

8. In a rock drill, the combination of a cylinder, a piston reciprocable therein, fluid distribution means for effecting admission and exhaust of motive fluid including a cylinder exhaust port governed by the piston, a drill steel arranged to be percussively actuated by said piston having a longitudinal passage for pressure fluid to its cutting end, means for placing said passage in communication with the cylinder when the piston is in the rearward portion of its travel, and means for closing said exhaust port to effect a hole blowing operation comprising a slide valve and longitudinally extending guideways formed on said cylinder exteriorly thereof for slidably receiving said valve, said slide valve maintained in its closed position outwardly against its guideways by the pressure of the fluid in the cylinder.

9. In a rock drill, the combination of a cylinder, a piston reciprocable therein, means for distributing live fluid pressure to each end of said cylinder including a distributing valve, a free exhaust port controlled by said piston, a drill steel arranged to be percussively actuated by said piston and having a longitudinal passage for conducting cleansing fluid to its cutting end, means for establishing communication between said drill steel passage and the front end of said cylinder when the piston is in the rear end thereof, and manually operable valve mechanism for closing said exhaust port and for directing a supply of pressure fluid to an area on said distributing valve to hold the latter in position to admit motive fluid to the front end of said cylinder to effect a hole blowing operation.

10. In a rock drill, the combination of a cylinder, a piston reciprocable therein, a throttle valve for controlling the fluid supply, means for distributing live pressure fluid from said supply to each end of said cylinder including a distributing valve, a free exhaust

port controlled by said piston, a drill steel arranged to be percussively actuated by said piston and having a longitudinal passage for conducting cleansing fluid to its cutting end, means for establishing communication between said drill steel passage and the front end of said cylinder when the piston is in the rear end of said cylinder, and a manually operable valve mechanism arranged along the side of said motor cylinder for closing said free exhaust port and for directing a supply of pressure fluid to an area on said distributing valve to hold the latter in position to admit pressure fluid to the front end of said cylinder to effect a hole blowing operation.

15 In testimony whereof I affix my signature.
